HENRY F. BICKEL, OF PLAINFIELD, NEW JERSEY, AND BLYTHE J. MINNIER, OF WATERTOWN, NEW YORK.

LUBRICATOR.

Application filed October 27, 1921. Serial No. 510,801.

To all whom it may concern:

Be it known that we, HENRY F. BICKEL and BLYTHE J. MINNIER, citizens of the United States, residing, respectively, at 5 Plainfield, in the county of Union and State of New Jersey, and at Watertown, in the county of Jefferson and State of New York, have invented certain new and useful Improvements in Lubricators, of which the 10 following is a specification.

This invention relates to cylinder lubrication and provides a device having particular utility when used for lubricating the cylinders of air compressors subject to wide 15 variations of discharge pressure and of temperature. These difficult conditions are met in the compressors used as a part of railway air brake systems as well as in many other important fields.

20 The most important advantages of the invention are the absence of moving parts, the inherent characteristic of varying the oil feed automatically according to the work being done by the compressor, and total automatic suspension of the oil feeding function when the compressor is shut down. Further refinements reside in details which 25 permit ready access to parts for cleaning and inspection, minimize any tendency for 30 clogging to occur, and preclude over-filling with oil.

Stated in its broadest terms the oil feeding operation depends upon the surging of compressed air back and forth through two 35 passages between the compressor cylinder, and a closed oil containing cup when the compressor is operating. The main passage leads directly from the compressor to the air space above the oil, but a branch or by-pass 40 leads from the main passage at a point above the level of the oil and opens into the cup at a point below the level of the oil. The by-pass is so proportioned relatively to the main passage that it functions to inject 45 a small quantity of oil into the main passage each time the air flows in said passage toward the compressor. The quantity so injected increases as the intensity of the air surges increases, thus giving a graduated 50 feed. The injection of the oil into a moving current of air is availed of to secure atomization of the oil, and the ports are specially located to enhance this effect. This special

location of the ports is also an important factor in securing the graduated oil feed 55 above-mentioned.

A practical embodiment of the invention is illustrated in the accompanying drawing, in which:—

Figure 1 is a vertical axial section of the 60 complete device.

Fig. 2 is a section on the line 2—2 of Fig. 1.

Fig. 3 is a view of a compound air compressor with two lubricators applied, one 65 for each air cylinder.

The body of the device forms the oil reservoir and consists of a hollow shell 6 and a ported member 7. The arrangement shown, in which the shell 6 is circular, and is cast 70 integrally with a central ported member 7, is preferred because of ease of manufacture, but other arrangements are obviously possible and may be preferable in particular cases. Whatever the form, it is desirable 75 to incline the bottom of shell 6 away from member 7 as shown at 8 so that any sediment which may be carried by the oil will be deposited at points remote from member 7 in which the oil feeding port is formed. 80

The member 7 is formed with a main air passage 9 which communicates with the interior of shell 6 by a port 10 slightly smaller than passage 9. This is located near the top of shell 6, and above the highest oil level 85 that may exist in shell 6. At its lower end the passage 9 is enlarged and internally threaded as indicated at 11 to receive a pipe connection to the air cylinder.

Directly opposite port 10 is a port 12 90 slightly smaller than port 10. This port is connected by a vertical passage 13 of approximately the same diameter with a relatively minute port 14 opening into shell 6 near the bottom thereof. This port 14 is 95 the oil port referred to above and its height marks the lowest level from which oil can be fed from the lubricator.

These ports are formed by the familiar practice of drilling and plugging as is 100 clearly indicated in the drawing. The plug 15 opposite port 14 is large and is threaded so as to be removable. This permits port 14 and the interior of shell 6 to be cleaned readily.

The oil-filling port 16 is closed by a

threaded plug 17 which seals the opening by means of a gasket 18. The port 16 is located below the top of shell 6 so that air is always trapped in the top of shell 6 and 5 overfilling is precluded.

The lubricator may be mounted in any convenient manner, but it is preferred to provide a boss 19 through which passage 9 extends, and to thread this boss externally 10 as shown at 20. The boss 19 then screws into a lubricator bracket 21 and is locked by a check nut 22.

A fitting 25 is screwed into the threads 11 and together with a pipe 23 connects the 15 passage 9 with a port 24 leading through the head of the air cylinder to be lubricated. In Fig. 3 two lubricators are shown each connected to the working space of the corresponding compression cylinder of a cross 20 compound compressor. Thus the passage 9 of each lubricator is subject to the pressure fluctuations in one working space of the corresponding air cylinder, and in the case of a cross compound compressor these pressure 25 fluctuations are different in the two cylinders.

Assuming that the lubricators are connected as shown in Fig. 3, and that they each contain a suitable quantity of oil, their 30 operation will be readily understood.

Low pressure air cylinder.—On the compression stroke of the piston, air flows to the interior of shell 6, so that at the end of such stroke substantially the pressure of discharge (i. e., the intermediate pressure of the compressor) will exist within shell 6. So soon as the suction stroke starts pressure in the working space of the compressor will drop almost instantly below atmospheric 35 pressure and the pressure in shell 6 will cause a sudden blast of air through port 10 and passage 9, which because of the restricted size of port 10 will continue for an appreciable time. During the continuance of 40 such blast a small jet of oil will be projected through port 14, passage 13 and port 12. This oil meeting the air current entering port 10 will be atomized and carried by the air into the cylinder.

High pressure air cylinder.—The action here is similar to that in the low pressure cylinder except that the limiting pressures are different. At the end of the compression stroke substantially the pressure of discharge 45 from the pump will exist within shell 6. When the suction stroke of the high pressure piston starts the pressure in the working space is subject to a sudden drop the low pressure limit being determined by 50 the dimensions and relative timing of the two cylinders. The effect of fluctuating pressure in the working space and the connected lubricator is the same as before described with reference to the low pressure 55 air cylinder.

Obviously the lubricator is applicable in the same manner to single stage compressors its action being merely dependent on the pressure fluctuations in the working space of the compressor.

The opposed relation of ports 10 and 12 has an important effect on the regulative function by which a graduated feed of oil is given according to the work being done by the compressor. It has been found that the 70 size of port 14 does not alone control the regulative action but that the opposed relation of the ports 10 and 12 is largely responsible for the graduated feed.

The opposed relation of ports 10 and 12 is 80 also essential to the securing of the best atomizing effect, and thorough atomization of the oil is an important factor in successful lubrication. A marked advantage is that the oil so atomized is carried directly 85 to the cylinder by an air current flowing at high velocity at the moment of atomization. This prevents settling of the atomized oil out of the air current.

The relative sizes of the ports and 90 passages have already been stated generally, and except as generally limited in the claims are subject to variation to secure the desired rate of feed. The size of port 14 has a direct regulative effect, but if varied widely 95 will require co-ordinated variations in other ports and passages.

Such dimensions depend on various conditions more or less characteristic of the particular installation, but in order to disclose 100 fully one successful embodiment the following port and passage dimensions, which give peculiarly good results with an 8 $\frac{1}{2}$ inch air brake compressor, working against a normal reservoir pressure of 132 pounds per square 105 inch, are given. The numbers refer to reference numerals on the drawing and the dimensions are diameters in inches.

Passage 9	0.1875	
Port 10	0.144	110
Port 12	0.1285	
Passage 13	0.125	
Port 14	0.031	

These dimensions as well as other details of the form of the device are subject to 115 considerable variation to meet the requirements of the particular cases.

What is claimed is:

1. A lubricator for compressors of the reciprocating type, comprising in combination 120 a closed shell adapted to contain oil and a confined body of air, said shell being provided with two ports, one an air port leading to the confined air space and the other a restricted oil port leading to the oil space, 125 through which the flow of oil from the shell is opposed by gravity; and means for connecting said ports with the working space of a compressor.

2. A lubricator for compressors of the re- 130

ciprocating type comprising in combination a closed shell adapted to contain oil and a confined body of air, said shell being provided with a passage and two ports opposed 5 to each other at their junctions with said passage at a point above the level of oil in said shell, one of said ports connecting said passage with the space within said shell above said oil, and the other of said ports 10 being in restricted communication with the interior of said shell below the surface of said oil; and means for connecting said passage with the working space of a compressor.

3. A lubricator for compressors of the reciprocating type comprising in combination a closed shell adapted to contain oil and a confined body of air, said shell being provided with a passage and two ports opposed to each other at their junctions with said 15 passage, at a point above the level of oil in said shell, one of said ports connecting said passage with the space within said shell above said oil, and the other of said ports being smaller, and being connected by a second 20 passage with a still smaller port leading to the interior of said shell below the level of oil therein; and means for connecting the 25

first named passage with the working space of a compressor.

4. The combination of a closed shell adapted to be partially filled with oil and affording an air space above said oil; an air compressor of the reciprocating type; a constantly open connection between said air space and a working space of said compressor; and a more restricted constantly open connection between the first-named connection and the interior of said shell below the level of the contained oil. 30 35

5. The combination of a closed shell adapted to be partially filled with oil and affording an air space above said oil; an air compressor of the reciprocating type; a constantly open connection between said air space and a working space of said compressor; and a more restricted constantly open connection leading from the interior of said shell below the level of the contained oil to said first named connection above the level 40 45 of said oil. 50

In testimony whereof we have signed our names to this specification.

HENRY F. BICKEL.
BLYTHE J. MINNIER.
